C. L. GOODRUM.
TELEPHONE EXCHANGE SYSTEM.
APPLICATION FILED DEC. 31, 1919.

1,387,255.

Patented Aug. 9, 1921.

UNITED STATES PATENT OFFICE.

CHARLES L. GOODRUM, OF NEW YORK, N. Y., ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,387,255.

Specification of Letters Patent. Patented Aug. 9, 1921.

Application filed December 31, 1919. Serial No. 348,579.

To all whom it may concern:

Be it known that I, CHARLES L. GOODRUM, a citizen of the United States, residing at New York, in the county of New York and State of New York, have invented certain new and useful Improvements in Telephone-Exchange Systems, of which the following is a full, clear, concise, and exact description.

- 10 This invention relates to telephone exchange systems, and more particularly to circuit arrangements for selector switches employed in automatic and semi-automatic telephone exchanges.
- 15 In systems employing automatic switching apparatus for extending connections from a calling to a called subscriber, it is customary to control such switches by means of impulse-sending devices at the calling station. These impulse senders or calling devices are of various forms and are capable of sending impulses varying in character. For example, some impulse senders are designed to send a series of impulses corresponding to the digit of the number desired in which all of the interruptions between said impulses are of equal length, while others are designed to send a series of impulses in which all of the interruptions between impulses are of equal length except the last which is relatively longer than the preceding ones. An impulse-sending device of the latter nature is disclosed in Patent No. 1,158,951 of November 2, 1915, to A. H.
- 20 30 35 Adams *et al.* In the well-known type of selector switch a controlling relay for sending impulses to an operating magnet at each interruption of the line circuit co-operates with a slow-to-release relay which is energized at the first closure of the line circuit and remains energized during the sending of a series of impulses. In the common type of selector switch a second slow relay similar to the one mentioned above is used to control a so-called side switch through the medium of a magnet, the side switch being advanced after each series of impulses to change local circuits in preparation for the hunting movements. Difficulty has been experienced with the ordinary selector switch when different type senders have been used, due to the stepping magnet of the switch not operating to step the switch in accordance with the digits set up at the impulse sender since, where the last interruption was longer than the preceding ones the side switch

would operate before the last impulse was sent.

It is, therefore, an object of this invention to provide a new and improved circuit arrangement for a selector switch, whereby the operation of the stepping magnet for setting the switch in relation to a group of trunk terminals is independent of the current impulses sent out by the impulse sender at the calling station.

In the present embodiment of the invention, the stepping magnets for operating the selector switch are controlled by a relay in a local impulse circuit, which relay is in turn controlled in the directive selective movements of the switch by the line relay. The circuit arrangement is such that the impulse relay is shunted during the closure of the line circuit, said shunt being broken at each interruption during the sending of impulses, thereby permitting the energization of the impulse relay. Actuation of the impulse relay closes a circuit for the stepping magnets, which, in turn, at their contacts again form a short circuit path for the winding of the impulse relay.

The drawings represent diagrammatically a portion of a telephone exchange system employing the present invention. Only so much of the circuit arrangements and apparatus is shown as is necessary for a clear understanding of this invention.

The mechanical construction and the operation of the step-by-step selector switches and other apparatus used in building up a connection between a calling and called subscriber are well known to those skilled in the art, and therefore, in the present disclosure a detailed description will be given only of the operation of the selector switch utilized in the establishment of a connection.

The subscriber at substation A, desiring to establish a connection with substation B, removes his receiver from the switchhook and causes a trunk finder or line switch C, to select, in a well-known manner, an idle trunk leading to a selector switch D. As soon as the wipers of switch C are set on the terminals of the calling line, a circuit is closed from grounded battery through the left-hand winding of line relay 4, wiper 5 of a side switch associated with selector switch D, brush 7, terminal 10, loop of the substation A, terminal 9, brush 8, side switch wiper 6, to right-hand winding of relay 4 to ground. Relay 4 upon energization closes a circuit

from ground through its right armature and front contact, through winding of slow-to-release relay 11 to grounded battery. Relay 11 upon energization prepares a circuit for relay 14 as follows: grounded battery, resistance 12, front contact and left hand armature of relay 11 and winding of relay 14 to ground. Relay 14 does not operate at this moment due to its being shunted at its right armature and back contact and left armature and front contact of relay 4 to ground.

The calling subscriber now operates his impulse sender S, which may be of the type disclosed in the patent heretofore mentioned, to send a series of impulses over the line to cause the setting of the selector switch D. Upon the first interruption of the line circuit, line relay 4 releases its armatures, thereby removing the shunt at its left-hand armature for relay 14, causing energization of the latter over the path heretofore traced. Energization of relay 14 establishes a circuit for primary stepping magnet 21, over the following path: ground, armature and front contact of relay 14, side switch wiper 20 in its first position, winding of primary stepping magnet 21 to grounded battery. Upon energization of primary stepping magnet 21, its armature is attracted and a shunt path is prepared for relay 14 as follows: grounded battery, resistance 12, front contact and left hand armature of relay 11, armature and front contact of magnet 21, side switch wiper 50 and its first contact, and front contact and left-hand armature of relay 4 to ground. This shunt path is completed at the end of the interruption of the line circuit, due to the armature of relay 4 being attracted when the second impulse of current is sent over the line. This operation is repeated for all impulses of the series.

In accordance with the nature of the impulse sender herein referred to, the last interruption in a series of impulses will be a comparatively long one which results in a comparatively long deenergization of the line relay and the closure of the back contact and right armature thereof to ground. This results in the energization of escape magnet 15 over the following path: grounded battery, winding of magnet 15, side switch wiper 16, in its first position, resistance 17, front contact and right-hand armature of relay 11, back contact and right-hand armature of relay 4 to ground. Magnet 15 is of the slow-to-energize type and does not receive sufficient current during the preceding interruptions to energize. As soon as the sending out of impulses ceases and the right armature of relay 4 is maintained attracted for a relatively long interval, magnet 15 is deenergized, thus moving the side switch brushes into position 2. Relay 14 was energized and consequently energized the step-

ping magnet 21, at the beginning of the interruption in the line circuit, so that the last directive movement of the switch was completed before the side switch was moved into position 2. In position 2 of the side switch wipers, primary magnet 21 is disconnected and secondary magnet is connected to ground over the front contact and left-hand armature of relay 14, relay 14 having been energized over the following path: 75 grounded battery, resistance 12, front contact and left-hand armature of relay 11, winding of relay 14 to ground.

Under the control of magnet 22, the wipers of the selector switch are stepped over the terminals thereof until an idle trunk is reached. As soon as test brush 26 of the selector switch D reaches the terminal of an idle trunk 27, to which ground will be connected, a circuit is closed from this ground through brush 26, side switch wiper 16 in its second position, winding of magnet 15 to grounded battery. The escape magnet 15 will again be energized causing the wipers of the side switch magnet to move into position 3, in which position the calling substation line is extended through the wipers 5 and 6 of the side switch to another switching mechanism, such as a selector or connector. The remainder of the desired connection may be established in a similar manner.

When the called subscriber replaces his receiver on the hook, the succeeding switching apparatus (selector or connector) will be restored to normal, causing ground to be placed upon the terminal 27, engaged by brush 26. This will close a circuit from ground through brush 26, side switch wiper 19 in its third position, off-normal contact 40 and winding of release magnet 105 30 to grounded battery. Release magnet 30, upon energization, closes a locking circuit for itself from grounded battery through its winding and off-normal contact 40 and armature and front contact to ground. Under the control of release magnet 30, the selector switch D and the associated side switch will be restored to normal, the locking circuit of the release magnet being maintained closed at its off-normal contact until selector switch D has been restored to its normal position. After the receiver of the calling substation A has been replaced and the side switch has been restored to normal, a ground is sent through the right-hand armatures and back contacts of relays 4 and 11 through side switch wiper 31 in its first position to the line or trunk finder C for causing the release of this switch.

Should the subscriber at substation A abandon the call before sending out impulses, he would replace his receiver on the switchhook, and cause thereby the deenergization of line relay 4 and slow release re- 130

lay 11. Ground would thereupon be placed upon brush 32 of the line finder through the right armatures and back contacts of relays 4 and 11, and side switch 31 to cause the 5 release of the line finder.

Should the subscriber abandon a call and replace the receiver upon the switchhook after the first set of impulses have been sent, *i. e.*, when the side switch wipers are in position 2, relays 4 and 11 would be deenergized and a circuit would be closed for release magnet 30 over the path previously traced which would cause the restoration of the selector and line switch or trunk finder to 10 normal as heretofore described.

What is claimed is:

1. In a telephone exchange system, incoming and outgoing groups of lines, a selector switch for extending an incoming to an outgoing line, an impulse sender associated with said incoming line for sending a series of impulses thereover, a directively controlled magnet for setting said selector switch in operative relation to a group of outgoing lines, an automatically operating magnet for moving said selector over lines in the selected group, a line relay responsive to closures in said incoming line circuit, a slow-acting relay energized during the sending of a series of impulses, an impulse relay for controlling the actuation of said directly controlled and said automatically operating magnets, a winding for said impulse relay, means for shunting said impulse relay upon actuation of said line relay, means for energizing said impulse relay, and a shunt circuit for the winding of said impulse relay including contacts on said magnets effective upon energization of said magnets for causing the deenergization of said impulse relay. 20

2. In a telephone exchange system, a line terminating in an automatic switch having primary and secondary operating magnets, an impulse sender for sending a series of impulses over said line, and three relays only for controlling the actuation of said magnets, one of said relays being energized during the sending of each impulse of current, another of said relays being energized 45 during the sending of a series of impulses, and the third relay being energized during the intervals between impulses.

3. In a telephone exchange system, a line, an automatic switch, a stepping magnet therefor, an impulse sender for sending a series of impulses over said line, a line relay responsive to each of the current impulses of a series, a slow acting relay energized during the sending of all the impulses of a series, an 50 impulse relay energized at each interval between impulses for controlling said stepping magnet, and means for shunting the winding of said impulse relay upon its energization.

4. The combination with a stepping magnet, of a stepping relay having an armature and contact for closing a circuit energizing said stepping magnet, a winding for said stepping relay, a line circuit, a line relay, an impulse sender for sending a series of impulses over said line to said line relay, and a shunt for the winding of said stepping relay effective when said line circuit is closed, said shunt being removed when said line circuit is interrupted. 65

5. The combination with a stepping magnet, of a stepping relay having an armature and contact for closing a circuit for energizing said stepping magnet, a winding for said stepping relay, a line circuit, a line relay, a slow-acting relay, an impulse sender for sending a series of impulses over said line to said line relay, a shunt for the winding of said stepping relay effective when said line circuit is closed, said shunt being removed when said line circuit is interrupted, and a second shunt for the winding of said stepping relay effective when said line circuit is closed and said stepping magnet is energized. 70

6. In a telephone system, an automatic switch having a plurality of operating magnets, a relay common to said magnets, means for associating the relay successively with said magnets, means for intermittently energizing the relay to operate said magnets, and means operable by the magnet associated with the relay to intermittently short-circuit the winding of the relay. 75

7. In a telephone system, a calling station, an automatic switch for extending a call therefrom, a line relay for said switch, a sender for said station for transmitting impulses to said line relay, a stepping relay, a circuit controlled by contacts of said line relay completed for said stepping relay at the beginning of each impulse for operating said stepping relay, a magnet for operating said switch controlled by said stepping relay, and means for short-circuiting said stepping relay when said magnet operates. 100

8. In a telephone system, a calling station, an automatic switch for extending a call therefrom, a line relay for said switch, a sender at said calling station for intermittently interrupting a circuit including said line relay, a stepping relay, a circuit closed for said stepping relay at each deenergization of said line relay, a stepping magnet for said switch controlled by said stepping relay, and means for deenergizing said stepping relay at the end of each interruption in the circuit of said line relay. 105

In witness whereof, I hereunto subscribe my name this 30th day of December A. D., 1919. 110

CHARLES L. GOODRUM.
